UNITED STATES PATENT OFFICE.

CHARLES W. TURNER, JR., OF MERIDEN, KANSAS.

WASHING-MACHINE.

SPECIFICATION forming part of Letters Patent No. 357,744, dated February 15, 1887.

Application filed September 3, 1886. Serial No. 212,601. (No model.)

To all whom it may concern:

Be it known that I, CHARLES W. TURNER, Jr., of Meriden, in the county of Jefferson and State of Kansas, have invented a new and Improved Washing-Machine, of which the following is a full, clear, and exact description.

My invention relates to washing-machines, and has for its object to produce a machine of simple and cheap construction for use in connection with an ordinary wash-tub, wherein the clothes are washed by the continuous forcing of water through them, and wherein, also, they are subjected to little friction, and consequently but slight wear.

The invention consists in the construction and combination of the several parts, as will be hereinafter fully set forth, and pointed out in the claims.

Reference is to be had to the accompanying drawings, forming a part of this specification, in which similar letters of reference indicate corresponding parts in all the figures.

Figure 1 is a perspective view of my washing-machine with one side thereof partially broken away, and Fig. 2 is a central longitudinal section thereof. Fig. 3 is a plan view of a modified form of dasher.

The side pieces, 1 and 2, of my washing-machine, which is adapted for use in connection with a tub, are provided each with a central vertical slot, 3, cut therein from a point about an inch and a half from the bottom to about half the height of said sides. The tops of the said side pieces, 1 and 2, at the ends thereof, are beveled to receive downwardly-inclined end pieces, 4 and 5, whose lower edges, 6, are made convex to conform to the inner side contour of the tub 20, (shown in dotted lines, Fig. 2,) and the outer edges, 7, of the said side pieces, 1 and 2, are also beveled for the same purpose. A transverse beam, 8, is usually employed as an additional support for the inclined end pieces, 4 and 5, and an extra brace for the side pieces of the machine. The ends and upper center portion of the said machine are left entirely uncovered.

The two cross-bars 9 and 10, secured midway the inclined end pieces, 4 and 5, in any approved manner adapted to project upward therefrom and unite at an angle over the center of the machine, are provided at their in-

tersection with a bearing, 11, preferably of metal, purposed to receive a U-shaped bar, 12, having horizontal outwardly-projecting ends 13.

The dasher 14, used in connection with my machine, is usually constructed with an under rectangular flat-faced board, 15, provided with central side pivot-pins, 16, adapted to engage the vertical slots 3 of the side pieces, 1 and 2, and an upper rectangular board, 17, the ends of which are beveled downwardly and made to extend beyond the ends of said under board, 15, to which it is attached.

In Fig. 3 a modification of the dasher is shown, the under board, 15, being provided upon the top with a series of slats, 18, attached thereto. The form of dasher shown in Figs. 1 and 2 is, however, preferably used.

The dasher is operated by means of uprights 19, secured thereto at right and left of the center, adapted to extend vertically upward a convenient distance upon each side and above the inclined beams 9 and 10, where they are united by handle 20. The motion of the said dasher is controlled by the engagement with the inner faces of said standards 19 of the horizontal ends 13 of the U-shaped bar 12.

In the operation of my washing-machine, as the handle is moved to one side, the U-bar 12 imparts to it a circular upward movement, as shown in dotted lines, Fig. 2. The dasher while being lifted in a vertical plane, through the engagement of the pins 16 with the slots 3, is tipped at an angle in opposite direction to the handle, and as the handle is brought forward the dasher gradually assumes a horizontal position, and with a rocking motion, as the said handle passes the center, again rises in a vertical plane to assume a reverse angular position, and so on, until brought finally to rest, as also shown in dotted lines, Fig. 2. By this movement of the dasher the water is forced downwardly and outwardly upon each side, and the continuous forcing of the water through the clothes thoroughly washes the same, subjecting them to little friction, and consequently but slight wear.

The construction is cheap and simple, and the complete machine is adapted for use with any tub, clamps or other fastenings being unnecessary, as the operator in working the ma-

chine will naturally bear down upon the handle, which serves to hold the machine in place and impart sufficient pressure to the clothes.

A wringer can conveniently be used upon 5 the side of the tub opposite the sides of the machine.

Having thus described my invention, what I claim as new, and desire to secure by Letters Patent, is—

- 10 1. In a washing-machine, the combination, with the side pieces, 1 and 2, provided with vertical slots 3, inclined end pieces, 4 and 5, and the united inclined beams 9 and 10, of the U-bar 12 and the standards 19, provided 15 with handle 21, together with the rectangular dasher 14, provided with side pins, 16, substantially as shown and described, and for the purpose herein set forth.

2. In a washing-machine, the combination, with the side pieces, 1 and 2, provided with 20 vertical slots 3, beveled top and ends 7, the inclined end pieces, 4 and 5, having convex outer edges, 6, and the united inclined beams 9 and 10, provided with a central bearing, 11, of the U-bar 12, standards 19, having attached handle 20, together with a rectangular dasher, 14, provided with beveled ends and side pins, 16, substantially as shown and described, and for the purpose herein set forth.

CHARLES W. TURNER, JR.
